UNITED STATES PATENT OFFICE.

RAY P. PERRY, OF UPPER MONTCLAIR, NEW JERSEY, ASSIGNEE TO THE BARRETT COMPANY, A CORPORATION OF NEW JERSEY.

PROCESS OF MANUFACTURING FELTS.

1,307,750.

Specification of Letters Patent. Patented June 24, 1919.

Application filed October 9, 1917. Serial No. 195,657.

To all whom it may concern:

Be it known that I, RAY P. PERRY, a citizen of the United States, residing at Upper Montclair, in the county of Essex and State 5 of New Jersey, have invented certain new and useful Improvements in Processes of Manufacturing Felts, of which the following is a specification.

In my co-pending application filed April 10 12, 1917, bearing Serial No. 161,670 and entitled "Felts and processes of making the same", I have disclosed and claimed a process of manufacturing felts and the resulting felts themselves, wherein there is employed, 15 in addition to the usual paper-making stock, a comminuted fusible waterproofing material, generally of a bituminous nature, and preferably in filamentary form, the waterproofing material being in the preferred 20 practice added to the watery pulp present in the beaters commonly employed in the manufacture of paper. In practising the above invention on a large or commercial scale, some difficulty has been experienced due to 25 the fact that during the course of the manufacture of the sheet, the same is customarily passed over a series of heated drying rolls. Since the felt or paper contains already incorporated therein comminuted fusible wa- 30 terproofing material, there is a tendency for the sheet to adhere to the heated rolls due to the slight fusion of the waterproofing material contained in the sheet in comminuted form. This adherence of the sheet to the 35 heated drying rolls is undesirable, not only because it has a tendency to render the sheet imperfect in parts, but also because the rolls after being in operation an appreciable length of time have a tendency to collect a 40 substantial quantity of the waterproofing material, such material preventing the sheet to be dried from coming into intimate contact with the drying roll and in this way, and in other ways that are obvious, inter- 45 fering with the most efficient operation of the drying rolls.

The object of my present invention is to provide means whereby the above disadvantages may be avoided. By my process the 50 drying of the wet sheet containing incorporated therein any desired amount of comminuted fusible waterproofing material, generally of a bituminous character, such as pitch or asphalt, and preferably in filamentary form, is accomplished, not by passing

the sheet to be dried over and in contact with a series of heated drying rolls, but by sending the moist sheet into a gaseous drying medium, such as hot air or superheated steam, preferably contained within a large 60 chamber or receptacle, where the drying takes place substantially out of contact with a highly heated solid surface.

Since the moist sheet generally possesses comparatively little mechanical strength, 65 and since it would otherwise have considerable tendency to warp, I have found it desirable to give the sheet some mechanical support while the same is passing through the gaseous or vapor drying medium. Preferably this support is given by causing the sheet to be dried to be passed over an endless belt consisting of a material such as sheet metal having therein a large number of perforations, so that the gaseous drying medium 70 may freely pass through the perforations and thereby come into contact with the side of the moist sheet which is supported directly against the said endless belt.

Referring to the drawing wherein I have 80 illustrated one form of device wherein my process may be carried out,

Figure 1 illustrates diagrammatically an apparatus wherein my process may be practised, and

Fig. 2 is a detail view of a portion of the endless supporting belt.

1 indicates the chamber or receptacle provided with the inlet 2 and the outlet 3 for the gaseous vapor drying medium, such as hot air or superheated steam. The sheet 4 of moist felt which is to be dried passes into the chamber 1 through the slot or aperture 5 near the upper portion thereof. The sheet 4 passes over the guide rolls 6 journaled in 90 the supporting member or frame 7 and is thereafter led on to the endless belt supporting member 8 which is supported upon the series of cylindrical members 9 provided with the gear or sprocket teeth 9' which serve as moving means for the endless belt. The teeth 9' of the members 9 fit into the apertures 8' at the edges of the endless belt 8. The endless belt 8 is furthermore provided with the perforations 8'' scattered throughout the width and length of the endless belt. In order to keep the sheet 4 against the perforated supporting member 8 during its passage through the chamber 1 there are provided the guide rolls 10, 10 preferably lo- 100 105 110

cated opposite those points of the moving belt 8 at which the members 9 are positioned. After the sheet 4 which is by this time properly dried leaves the last guide roll 5 10 it passes to the guide member 11 journaled in the frame or support 12 and finally passes out of the chamber 1 through the aperture or slot 13. Any suitable means (not shown) may be employed for rotating 10 the members 9, 9 thereby causing the movement of the belt 8 in the directions indicated by the arrows.

The operation of the above apparatus and the carrying out of my process therein are obvious from the description already given. 15 The sheet 4 in its passage through the chamber 1 which is filled with a gaseous or vapor drying medium, such as hot air or super-heated steam, entering the chamber 1 through 20 the inlet 2, is thoroughly and speedily dried. The supporting member 8 which is provided with numerous perforations so that the area of contact between the same and the sheet to be dried is as small as possible, prevents 25 the sheet 4 from becoming warped without, however, preventing free access of the drying medium to that surface of the sheet which is in contact with the member 8.

Throughout the claims wherever I refer 30 to the term "gaseous" I mean to include thereby vapor drying mediums as well.

What I claim is:

1. The process of manufacturing felts and the like, which comprises the steps of forming 35 a moist sheet of paper-making material containing incorporated therein fusible waterproofing material in comminuted form, and thereafter passing the moist sheet through a heated gaseous drying medium.

40 2. The process of manufacturing felts and the like, which comprises the steps of forming a moist sheet of paper-making material containing incorporated therein fusible waterproofing material in comminuted form, 45 and thereafter passing the moist sheet through a heated gaseous drying medium while supporting the sheet to prevent warping of the same.

3. The process of manufacturing felts and 50 the like, which comprises the steps of forming a moist sheet of paper-making material containing incorporated therein bituminous material in comminuted form, and thereafter passing the moist sheet through a heated gaseous drying medium.

4. The process of manufacturing felts and

the like, which comprises the steps of forming a moist sheet of paper-making material containing incorporated therein bituminous material in comminuted form, and there- 60 after passing the moist sheet through a heated gaseous drying medium while supporting the sheet to prevent warping of the same.

5. The process of manufacturing felts and 65 the like, which comprises the steps of forming a moist sheet of paper-making material containing incorporated therein fusible waterproofing material in filamentary form, and thereafter passing the moist sheet 70 through a heated gaseous drying medium.

6. The process of manufacturing felts and the like, which comprises the steps of forming a moist sheet of paper-making material containing incorporated therein fusible 75 waterproofing material in filamentary form, and thereafter passing the moist sheet through a heated gaseous drying medium while supporting the sheet to prevent warping of the same. 80

7. The process of manufacturing felts and the like, which comprises the steps of forming a moist sheet of paper-making material containing incorporated therein bituminous material in filamentary form, and thereafter 85 passing the moist sheet through a heated gaseous drying medium.

8. The process of manufacturing felts and the like, which comprises the steps of forming a moist sheet of paper-making material 90 contained incorporated therein, bituminous material in filamentary form, and thereafter passing the moist sheet through a heated gaseous drying medium while supporting the sheet to prevent warping of the same. 95

9. The process of manufacturing felts and the like, which comprises the steps of forming a moist sheet of paper-making material containing incorporated therein pitch filaments, and thereafter passing the moist sheet 100 through a heated gaseous drying medium.

10. The process of manufacturing felts and the like, which comprises the steps of forming a moist sheet of paper-making material containing incorporated therein pitch 105 filaments, and thereafter passing the moist sheet through a heated gaseous drying medium while supporting the sheet to prevent warping of the same.

In testimony whereof I affix my signature. 110

RAY P. PERRY.
